UNITED STATES PATENT OFFICE.

WILLIAM H. BENDRY, OF HANCOCK, MICHIGAN, ASSIGNOR OF ONE-FOURTH TO WILLIAM J. BENDRY AND ONE-FOURTH TO JAMES H. BENDRY, BOTH OF HANCOCK, MICHIGAN.

WATER-HEATING SYSTEM.

Application filed June 11, 1926. Serial No. 115,404.

The present invention appertains to new and useful improvements in water heating systems and has for its primary object the provision of heating means of the class described adapted primarily for association with a furnace whereby the water contained within the boiler thereof will be efficiently heated.

Another object of the present invention is to provide a water heating system of the class described including a plurality of heating coils adapted to be positioned within the fire box of a furnace together with new and novel connections between the coils and the boiler whereby a complete circulation of water through the boiler and the coils will be achieved.

Another object of the present invention is the provision of means disposed in the connections between the coils and the boiler whereby the circulation of the water through the coils and boiler may be stopped should the coils be broken or otherwise damaged.

Another object of the present invention is to provide means whereby the water will be run directly into the boiler during the time in which the coils may be broken or are being repaired.

Another object of the present invention is the provision of a water heating system of the class described which consists of a minimum number of parts, one which is inexpensive to manufacture, efficient in its operation and well-designed for the purposes for which it is intended.

Numerous other objects and advantages of the present invention will become more readily apparent during the course of the following description when taken in connection with the accompanying drawings.

In the drawings forming a part of this application and wherein like characters of reference denote corresponding parts throughout the several views:

Figure 1 is a side view, of one type of furnace showing the improved heating system associated therewith.

Figure 2 is a sectional view taken on line 2—2 of Figure 1.

Figure 3 is a side view of one of the coils. Reference now being had more particularly to the accompanying drawings wherein for the purpose of illustration has been disclosed a preferred embodiment of the pres-

ent invention, the letter A generally represents a furnace of any conventional or preferred construction and B the present improved water heating system associated therewith.

As stated above, the furnace A may be of any conventional or preferred construction so that a detail description thereof is not thought to be necessary. However, the type of furnace disclosed in the accompanying drawings includes the fire box 9 within which is arranged the fire grate 10 and above which is disposed the boiler 11, these being the parts of the furnace in connection with which the present improved water heating system is associated.

The water heating system B comprises in its construction a pair of coils 12 and 13 which may be of any desired shape and size and which are adapted to be positioned within the fire box 9 of the furnace at the opposite sides thereof and directly above the grate 10. The heating coils 12 and 13 are disposed longitudinally of the furnace and the forward ends thereof are connected by means of the transverse pipe 14 secured by one or more brackets 15 to the furnace directly beneath the boiler. Secured to the rear ends of the coils 12 and 13 are the outlet and inlet pipes 16 and 17 respectively, said inlet and outlet pipes extending transversely through and outwardly of the furnace as clearly shown in Figure 2.

Connected to the outer end of the outlet pipe 16 is the vertically disposed pipe 18 having connected to its upper end the substantially horizontal pipe 19 connected to the depending pipe 25 which leads into the top of the boiler 11. Disposed within the horizontal pipe 19 is a one-way valve 20 operating only in the direction indicated by the arrow while an ordinary cut off valve 21 is installed within the depending pipe 25 adjacent the top of the boiler 11.

Connected to the outer end of the inlet pipe 17 is one end of the horizontally arranged pipe 22 having connection approximately intermediate its ends with the boiler 11 through the medium of the substantially horizontally disposed pipe 23 identified as a control pipe which leads into the bottom of the boiler 11 and disposed within the length of the said pipe 23 immediately adjacent the pipe 22 is a conventional cut-off valve 24.

Carried by and communicating with the pipe 22 is a by-pass pipe 26 within which is installed a suitable cut-off valve 27. Disposed within the length of the pipe 22 are 5 the two one-way valves 28 and 29 operable only in the direction indicated by the arrows while also disposed within the length of said pipe 22 are suitable cut-off valves 30 and 31.

10 The free end of the pipe 22 is adapted to have connections with a suitable pump, not shown, which pump is adapted to force the water through the coils into the boiler 11. In the normal operation of the present invention, such as when it is desired to circulate the water through the coils 12 and 13 and boiler 11, the cut-off valve 31 is closed while the valves 27, 30, 21, and 24 are opened whereby the water will be pumped through 20 the by-pass pipe 26 into and through the coils 13 and 12 where it will be heated after which it will pass through the outlet pipe 16, pipes 18, 19, and 25 into the top of the boiler 11. The water is then permitted to 25 pass outwardly of the boiler through the pipe 23 into the pipe 22 and thence to the coils from which it will pass back into the boiler in the manner set forth above. Thus, a complete circulation of the water will at 30 all times be achieved. The one-way valve 28 will prevent the water from backing up in the pipe 22 while the one-way valve 20 will prevent the water from backing up in the pipe 19.

35 Should the coils 12 and 13, for one reason or another, become broken or otherwise damaged so that they will not properly function, the valves 27, 30 and 21 are closed while the valves 31 and 24 are opened with the result 40 that the water will be caused to flow directly into the boiler 11. The valves 27 and 30 will prevent any water from reaching

the coils while the valve 21 will prevent the water from passing outwardly of the boiler through the depending pipe 25. Thus, the 45 coils can be readily repaired after which the circulation of the water therethrough can again be resumed in the manner set forth above.

From the foregoing, it will be appreciated 50 that there has been provided a novel and simplified water heating system which will perform all of the functions and accomplish all of the objects claimed and it is to be further understood that while there has 55 been disclosed a preferred embodiment of the present invention, changes in the details of construction thereof may be resorted to without departing from or sacrificing the spirit of the invention so long as such 60 changes fall within the scope of the appended claim.

What is claimed is:

In combination with a boiler, a water heating system comprising a pair of coils in 65 communication with each other, a return pipe establishing communication between one of the coils and the top of the boiler, a water supply pipe communicating with the other coil, a control pipe communicating 70 with the bottom of the boiler and with said supply pipe, a by-pass pipe around the point of juncture of the control pipe with the supply pipe, a valve arranged in the supply pipe beyond the 75 juncture of the by-pass pipe with the supply pipe, valves in the by-pass pipe and control pipe whereby upon manipulation water flow to the coils may be cut off and the water passed directly through the control 80 pipe into the boiler.

In testimony whereof I affix my signature.

WILLIAM H. BENDRY.
